(57) CLAIM

(58) **Field of Classification Search**

The ornamental design for a contraceptive as shown and described.

USPC D24/141, 105, 107, 143
CPC A61F 6/00; A61F 6/08; A61F 6/06; A61F
6/14; A61F 2/005; A61F 2/0027; A61F
2/0036

DESCRIPTION

See application file for complete search history.

(56) **References Cited**

FIG. 1 is a perspective view of a contraceptive showing the claimed design;
FIG. 2 is a top view thereof, the bottom view being the same;
FIG. 3 is a side view thereof;
FIG. 4 is another side view thereof;
FIG. 5 is another side view thereof, the opposite side view being a mirror image thereof;
FIG. 6 is a cross-sectional view thereof, taken along line 6-6 of FIG. 5;
FIG. 7 is an enlarged view of a portion of the contraceptive labeled 7 in FIG. 4; and,
FIG. 8 is an enlarged view of a portion of the contraceptive labeled 8 in FIG. 4.

The dashed broken lines in the figures show portions of the contraceptive that form no part of the claimed design.

The dot-dash broken lines in FIGS. 4, 7, and 8 form no part of the claimed design.

1 Claim, 6 Drawing Sheets
